UNITED STATES PATENT OFFICE.

WILLIAM C. EVANS, OF SEDALIA, MISSOURI, AND SAMUEL M. BANCROFT, OF WICHITA, KANSAS, ASSIGNEES, BY MESNE ASSIGNMENTS, TO THE CARBURETOR LOCK CORPORATION, A CORPORATION OF NEW YORK.

CARBURETER-LOCK.

1,345,841.

Specification of Letters Patent.

Patented July 6, 1920.

Application filed June 10, 1918. Serial No. 239,278.

To all whom it may concern:

Be it known that we, WILLIAM C. EVANS and SAMUEL M. BANCROFT, citizens of the United States, residing, respectively, at Sedalia, in the county of Pettis and State of Missouri, and Wichita, in the county of Sedgwick, State of Kansas, have invented certain new and useful Improvements in Carbureter-Locks; and we do hereby declare the following to be a full, clear, and exact description of the invention, such as will enable others skilled in the art to which it appertains to make and use the same.

The object of the invention is to provide means whereby the feed valve of an internal combustion engine may be locked in a closed position when the engine is left unattended, so that an unauthorized person cannot turn on the fuel supply and start the engine. The invention is especially applicable to the engines of automobiles inasmuch as by the use of it an automobile may be safely left unattended without danger of being stolen.

Various types of liquid fuel locks have been devised. Some are located directly in the supply tanks. These are objectionable primarily because the valves employed cannot be operated by conventional types of cylinder-lock keys, and, secondarily, because most supply tanks are now disposed exteriorly of the car body in plain view, and the owners of these cars will invariably not submit to the installation of such devices solely because they mar the appearance of the tanks. Another class of locks is arranged at some convenient point between the terminals of the tube leading from the tank to the carbureter. These possess the same disadvantage with respect to the non-operativeness of the valve as do the tank locks, and in addition, a thief is afforded the opportunity to sever the flexible tube—and the tubes are almost universally flexible—immediately adjacent opposite sides of the valve, and then reconnect the severed terminals with a short piece of rubber tubing, or to connect the terminal which joins the carbureter to a temporary portable reservoir. Still another form of lock is disposed in the intake manifold of an internal combustion engine, but this is impracticable from a standpoint of installation, and impossible of installation in a number of lead-

ing makes of cars for the reason that manifolds have been entirely eliminated. Even if this contingency had not arisen it is extremely doubtful whether they would have proved thoroughly practical, as they must of necessity be placed in close proximity to the cylinders of the motor, and the heat radiated therefrom would obviously have a detrimental effect upon the delicate lock mechanism.

We have solved this perplexing problem by including a lockable valve as a part of the carbureter structure for controlling the flow of fuel therethrough. It is of extreme importance that the valve or valve casing be formed as an integral part of, or a unit of construction with the carbureter, whether this be done in the original process of manufacture, or subsequently permanently attached to the carbureter, as by welding or sweating of the connection. The underlying reason for this is that no point is left between the valve and the carbureter which may be disconnected, or expeditiously severed by an unauthorized person. In fact, the only ways in which the valve in its entirety may be removed, is by taking off the carbureter or by applying a torch or blowpipe flame to the welded or sweated connection—the former requiring so much time and the substitution of a new carbureter, and the latter being so hazardous, as to completely discourage and foil any attempt on the part of a thief to confiscate the vehicle, motor-boat or the like to which the lock valve is attached.

90
Referring to the drawings—

Figure 1 is a view in elevation showing the relation of the valve lock to the feed valve of a carbureter.

Fig. 2 is a vertical transverse section of the device.

Fig. 3 is a bottom plan view of the lock.

Fig. 4 is a top plan view of the valve.

Fig. 5 shows a modification.

Fig. 6 shows a further modification.

A is a carbureter of any ordinary type, having associated therewith a valve casing B which is provided with a rotary valve C.

D is a tubular casing or sleeve in which is secured by soldering or otherwise a Yale lock E having a key e. The key slot e' is exposed at the upper end of the tubular casing D so that the key e may be readily inserted

therein. The inner or lower end of the lock is provided with a slot e^2 , and the upper end of the valve B is provided with a similar slot b' .

- 5 Between the proximate ends of the valve C and the lock E is disposed a short connecting plate F extending at its respective ends into and loosely fitting said slots e^2 and b' , thus constituting a universal connection between the lock E and the valve C, to compensate for the eccentricity of the lock which, as will be seen, rotates on an axis that is non-alined with the axis of the valve. The connecting plate is maintained 15 in position by the adjacent parts of the structure, and is made thin relatively to the width of the slots e^2 and b' , in order to have sufficient freedom of motion to permit of the required universal movements.
- 20 In the modification shown in Fig. 6 the valve casing B and the sleeve D are arranged out of alinement in order to aline the axes of the valve and the lock. In this construction the slot e^2 is dispensed with 25 and the connecting plate is in the form of a tongue f' extending from the lower end of the lock into the slot b^2 at the top of the valve, this slot b^2 being diametrically disposed and of such width as to admit the 30 lower end of the tongue f' .

The valve casing B may be integral part of the carbureter bowl a , as shown in Fig. 1, or it may be an independent part as shown at B' in Fig. 5. If non-integral, the 35 valve casing may be provided with oppositely extending tubular projections b^2 , b^3 , which are, respectively, provided with male and female screw threads b^4 , b^5 , the female screw thread b^5 being engaged with the 40 male screw thread b^6 on the carbureter nipple b^7 . If the carbureter fuel-line connection member is of some other standard form than that shown and described, the corresponding connection devices of the lock 45 casing may be modified accordingly. The union of the screw threads b^6 , b^7 is made permanent by a mass of solder b^8 sweated into the space between the screw threads as shown in Fig. 5. If the part of the carbureter to which our device is directly applied, as a in Fig. 5, is normally removable 50 from the carbureter, an inspection is made to determine whether, with the device attached there would be sufficient room be- 55 cause of the proximity or remoteness of the motor or other elements, in which to turn the part carrying the device completely around, simultaneously remove the part and the device, and thus defeat the purpose of 60 the invention. If this could be accom- 65 plished—and even realizing that it would be necessary to then substitute a new part—we prefer to also sweat or weld part a to the body of the carbureter and thereby insure irremovability. Assuming that the

part could not be unscrewed, it would be left intact.

It will be observed that the valve casing, and the carbureter are devoid of a severable connection, and that in consequence of the 70 direct and permanent relationship between them the valve C, when closed and locked, prevents the admission of fuel to the carbureter, and that severance of the supply pipe will not open the passage into the carbureter. When the valve is closed and locked it is therefore impossible to supply 75 the carbureter with fuel from either the ordinary tank or from an auxiliary portable tank such as might be used if the fuel 80 duct were open beyond the supply valve.

The valve C is provided with stops c , c' lying in the path of a pin c^2 extending from the valve, the extent of movement permitted by the stops being only sufficient to allow 85 the valve to be either fully opened or fully closed. This limitation of movement prevents the key e from being turned to a position which admits of its withdrawal from the lock, except when the valve C is 90 closed. The key will therefore remain in the lock while fuel is flowing to the carbureter, but when the supply of fuel has been cut off, the key may be removed from the lock and carried away by the operator. 95

The invention is applicable not only to carbureters of automobiles and of motor boats, but to any internal combustion engine using vaporized or fixed gaseous fuel.

The valve casing cannot be removed from 100 the carbureter while the carbureter contains fuel, because the blow pipe flame is required to loosen the sweated connection, and special tools would have to be employed in order to open up the passage into the carbureter if 105 the carbureter and valve casing constitute one integral part. Furthermore, the application of a blow pipe flame to a carbureter would be extremely hazardous and impracticable. It will thus be seen that the theft of 110 an automobile equipped with our invention is impossible unless the machine is hauled away under the power of another machine. 115

Among other advantages flowing from the use of our invention is that when the valve 120 has been locked in closed position, only that quantity of fuel which is in the float chamber of the carbureter can evaporate or leak from the carbureter. This effects a very great saving, when it is considered that an 125 average of one pint of gasoline evaporates from a carbureter every twenty-four hours, and that a considerable number of carbureters leak because of defective needle-valves. Additionally, theft insurance is 130 eliminated, and the rate of fire insurance is reduced to a minimum.

Wherever the word "lockable" is used in the specification and claims, it signifies a lock which can be actuated by a special key 130

or by a contrivance, the operation of which is not known to the general public.

We wish it understood that in its generic aspects our invention comprehends the employment not only of the various means described, but of equivalent means for performing the recited functions. For example, we are not limited to the particular type of valve nor to the specific kind of lock. We desire to reserve the right to effect such modifications and variations as may come fairly within the scope of the appended claims.

Having thus described our invention what we claim is:

1. In a fuel locking mechanism for carbureters, the combination with a carbureter having a standard fuel-line connection, of a casing inclosing a fuel valve and a lock capable of retaining the valve in closed position, a fuel-line connection on the casing, and a connection integral with the casing and adapted for quick and permanent joiner to said carbureter connection, without modification of the latter.

2. In a fuel locking mechanism for carbureters, the combination with a carbureter having an integral fuel-line connection, of a casing inclosing a fuel valve and a lock capable of retaining the valve in closed position, a fuel-line connection on the casing, and a connection integral with the casing and adapted for quick and permanent joiner to said carbureter connection without modification of the latter. 30

3. In fuel locking mechanism for carbureters, the combination with a carbureter having an integral fuel-line connection, of a unitary casing inclosing a fuel valve and a lock capable of retaining the valve in closed position, a fuel-line connection on the casing, and a connection integral with the casing and adapted for quick and permanent joiner to said carbureter connection without modification of the latter. 35

40 In testimony whereof we affix our signatures.

WILLIAM C. EVANS.
SAMUEL M. BANCROFT.
